John E. Hale.

UNITED STATES PATENT OFFICE.

GEORGE M. HUBBARD, OF NEW HAVEN, CONNECTICUT, ASSIGNOR TO W. & E. T. FITCH, OF SAME PLACE.

BRIDLE-BIT.

SPECIFICATION forming part of Letters Patent No. 332,200, dated December 8, 1885.

Application filed October 12, 1885. Serial No. 179,633. (No model.)

To all whom it may concern:

Be it known that I, GEORGE M. HUBBARD, of New Haven, in the county of New Haven and State of Connecticut, have invented a new 5 Improvement in Bridle-Bits; and I do hereby declare the following, when taken in connection with accompanying drawings and the letters of reference marked thereon, to be a full, clear, and exact description of the same, 10 and which said drawings constitute part of this specification, and represent, in—

Figure 1, a face view of one part of the bit-bar and ring; Fig. 2, a longitudinal section through the same; Fig. 3, the ring detached 15 as prepared for introduction to its place in the bit-bar.

This invention relates to an improvement in that class of bits for bridles in which a ring-shaped loop is hinged in the outer end of the 20 bit, to which to attach the rein, and in which the ring is constructed with a single guard, and the invention relates particularly to the construction of the ring to form the joint; and it consists in constructing the ring open or 25 divided, one end having a guard formed thereon as an integral part of the ring, the other end constructed with a shank which will pass through the opening in the end of the bit-bar, the said shank having a stud on its end, 30 and in longitudinal line with the shank, to enter a corresponding recess in the opposite end of the ring, with a pin through that end of the ring, and through the said stud, as a means for locking the ring in place, and as more 35 fully hereinafter described.

A represents one part of the bit-bar, the other part not shown; B, the outer end or head of the bit-bar, through which is a vertical central opening, *a*, in which the ring is 40 to be pivoted; C, the ring, is in the usual shape. The ring is divided. From one end there extends the guard D, and that end of the ring is constructed with an upward projection, *b*, corresponding to the opening in the head of the bit-bar, and so as to form a shoulder around the projection to take a bearing upon the under side of the head of the bar, as seen in Fig. 2. The other end of the ring is constructed with a shank, E, the said

shank at the end of the ring corresponding 50 to the diameter of the opening through the head of the bit-bar, and so as to leave a shoulder, *d*, at that end of the ring. The length of the shank is such as to pass through the opening in the bit-bar and rest against 55 the projection *b* on the other end of the ring. On the end of the shank E is a concentric stud, *e*, and in the opposite end of the ring is a corresponding opening, *i*, into which the stud may enter, and transversely through 60 that end of the ring and the said opening a hole, *f*, is made, and a corresponding hole, *g*, in the stud, as seen in Fig. 3.

The ring is applied by introducing the shank E through the opening in the head of 65 the bar, then closing the other end of the ring to the opposite side of the head, and so as to bring the stud *e* into the opening in that end of the ring, and as seen in Fig. 2. Then a pin, *h*, is driven through the hole in that end of the 70 ring and through the hole in the said stud, thus securing the two ends of the ring firmly together, the shank E forming a pintle in the bar upon which the ring may turn. This construction, while it makes a strong connection 75 between the two ends of the ring, permits a neat finish to the ring at its junction with the head of the bit-bar, and without the use of solder or equivalent device for connecting the two ends of the ring. While this 80 construction is specially adapted to a half-cheek bit—that is, a bit with a single guard—it may be provided with the two guards, as indicated in broken lines, Fig. 1, or both 85 guards may be omitted.

From the foregoing it will be understood that I do not claim, broadly, a divided ring hinged to the bit-bar by a pintle on the one part extending through the head of the bit-bar and secured to the other part, but

What I do claim is—

In a bridle-bit, the bit-bar A, having the vertical opening through its outer end, combined with a divided ring, C, one end constructed with a projection, *b*, to enter the 95 opening in the head of the bit-bar, and also constructed with a recess, *i*, the other end of the ring constructed with a shank, E, corre-

sponding to the opening through the bit-bar, and the said shank constructed with a stud, *e*, corresponding to the opening *i* in the other end of the ring, the said shank extending 5 through the opening in the head, and into said recess in the other end of the ring, and there secured by a transverse pin through that end of the ring and stud, substantially as described.

GEORGE M. HUBBARD.
